JOHN MELISCH, OF BENLD, ILLINOIS, ASSIGNOR OF ONE-HALF TO JOSEPH ZBOYOSKI,
OF BENLD, ILLINOIS.

ICE CRUSHER OR GRATER.

1,092,658.

Specification of Letters Patent. Patented Apr. 7, 1914.

Application filed August 14, 1913. Serial No. 784,795.

To all whom it may concern:

Be it known that I, JOHN MELISCH, a subject of the Emperor of Austria-Hungary, residing at Benld, in the county of Macoupin 5 and State of Illinois, have invented certain new and useful Improvements in Ice Crushers or Graters, of which the following is a full, clear, and exact description, reference being had to the accompanying drawings, 10 forming a part hereof.

My invention has relation to improvements in ice crushers or graters; and it consists in the novel details of construction more fully set forth in the specification and 15 pointed out in the claim.

In the drawings, Figure 1 is a side elevation of the crusher, with parts broken away; and Fig. 2 is a vertical cross-section on the line 2—2 of Fig. 1.

20 The object of my invention is to construct an ice crusher or grater which will find ready service in the household, bar-rooms, restaurants and like places, the device being intended more particularly to crush or grate 25 large pieces of ice and thereby furnish necessary material for iced-tea, mixed drinks, water, and other beverages, or to furnish crushed ice for fruits, salads and the like.

A further object is to construct a crusher 30 or grater which may treat the ice with a minimum amount of waste; one which is simple, cheap, durable, and one possessing further and other advantages better apparent from a detailed description of the invention which is as follows:—

Referring to the drawings, B represents a box, receptacle or container supported at an incline on legs L, L, and provided at the rear with a hinged door D adapted to be 40 locked by a spring latch a. No claim is made to these features *per se* as they are well understood in the art. Mounted across the box at the lower or depressed end thereof in bearings 1, 1, is the shaft 2 of an open 45 cylindrical cutter-frame or cage, said frame comprising the terminal heads 3 composed of a series of radiating arms, whose outer ends are connected by longitudinal parallel bars 4, which conform to the peripheral elements of said cylinder. Disposed along the bars 4 are a series of square or polygonal radially disposed openings o, those of one bar being staggered with those of an adjacent bar, the said openings each receiving the 55 square (or polygonal) shank 5 of a cutter 6,

the shank terminating on the inside of the cylindrical frame in a screw-stem 7 over which is passed a retaining or clamping nut n bearing against the inner face of the bar. The nuts n being on the inside of the cylinder are thus out of the way and do not readily work loose. As seen to best advantage in Fig. 2, the cutter head 6 is shouldered to the outer face of the bar 4, there being an offset between the shank 5 and the base of the 60 cutter head. The cutter head or cutter proper has an inner concaved face h, two basal flat side faces d, an outer or rear flat face e and side shearing faces m, m, converging in a convex cutting edge t, the faces 65 m, m, edge t, and face h tapering to a cutting tip x, the head as a whole being disposed at an angle to the common axis of the shank and stem. The shaft is provided with a crank-handle C on the outside of the box, 70 and in actual operation the shaft must be rotated in proper direction to cause the tips x to cut into the ice as the latter gravitates or slides toward the cutter-frame, along the inclined bottom of the box B. Immediately 75 beneath the cutter frame is a discharge hopper H terminating in a delivery spout S for the crushed or grated ice.

The operation of the grater may be described as follows: The house-wife or attendant opens the door D and introduces blocks of ice I into the box or container B and then closes the door. Thereupon rotation is imparted to the cutter-frame clockwise or in proper direction to cause the 80 teeth or cutter-heads 6 to dig into the ice as the latter gravitates toward the cutters along the inclined bottom of the box. The cutters grate the ice into small fragments which drop through the hopper H and discharge spout S thereof into any suitable receptacle (not shown). The cutters being readily accessible and removable, a broken cutter may be readily replaced by a fresh 85 one, or a cutter may be removed and readily sharpened and quickly put back on the rotary frame. The concave face h is the "bottom" face being the face which advances toward the ice and dips toward the bottom of the receptacle, as the cutter approaches 90 said bottom. The several cutters approach to within a short distance of the box bottom so as to better cut the ice and not lift the same off the bottom, the lumps of ice 95 being thereby cut or grated into small pieces 100 105 110

desirable for various domestic and other purposes.

Features shown but not alluded to are well known in the art and require no detailed description in the present connection. The invention need not of course be limited in its application to the grating of ice. An inspection of Fig. 1 shows that the ends of the cutters or cutter heads, notably the faces 10 m , m , and edges t thereof, are deflected at an angle to the radii of the cylinder along whose periphery the cutters are disposed, the free ends of the edges t being substantially tangent to the outer circles described 15 by the cutters.

Having described my invention, what I claim is:

An ice grater comprising a closed receptacle having a charging opening and provided with an inclined flat bottom, said bottom having a discharge opening at the depressed end thereof, a rotary frame mount-

ed across the receptacle and confined therein above the depressed end of the inclined bottom, a series of cutters disposed on the 25 frame and adapted to sweep wholly above the plane of the inclined bottom in circular paths through the ice with the rotation of the frame and tangentially to the edge of the opening over which the crushed ice is 30 delivered, said cutters being distributed longitudinally along the periphery of the rotary frame in distinct rows and spaced apart, the cutters of one row being in staggered relation with the cutters of an adjacent row, and dipping toward the bottom of the receptacle during the cutting operation.

In testimony whereof I affix my signature, in presence of two witnesses.

JOHN MELISCH.
